CAP FORM FEEDING ATTACHMENT FOR
PAPER BOTTLE CAPPING MACHINESIrving F. Mandell, North Quincy, Mass., assignor
to Reinforced Paper Bottle Corporation, New
York, N. Y., a corporation of Delaware

Application July 14, 1936, Serial No. 99,575

8 Claims. (Cl. 271-27)

My invention relates to improvements in cap form feeding attachments for paper bottle capping machines, and the object of the invention is to devise means for successively feeding cap forms from a vertical stack of forms into a capping machine conveyor, means for preventing more than one form being fed at a time by holding the upper cap forms separated from the underlying forms, and means for automatically 5 maintaining the top of the stack in a feeding position as the height of the stack decreases and to provide a stack holder in which the stack may be easily inserted and held firmly in position, and it consists essentially of the arrangement and 10 construction of parts all as hereinafter more particularly explained.

Fig. 1 is a front view of the cap feeding mechanism.

Fig. 2 is a side view thereof.

Fig. 3 is an elevational plan view of the same mechanism.

Fig. 4 is a perspective view of the mechanism for automatically elevating the cap forms to their feeding position.

Fig. 5 is a plan sectional view taken on line 5-5 Fig. 1, showing the cap form retaining device and the position of the two blower agitators.

Fig. 6 is an enlarged plan sectional view taken on line 6-6 Fig. 1, showing the ratchet drive for 30 elevating the cap forms.

Fig. 7 is a sectional view taken on line 7-7 Fig. 1, showing the parts illustrated in Fig. 6.

Fig. 8 is a sectional view taken on line 8-8 Fig. 1 showing the details of the suction member 35 and the mechanism for detecting the height of the cap forms contained in the magazine.

Fig. 9 is a sectional view taken on line 9-9 Fig. 3, showing the means by which the suction member is operated and also the suction valve and 40 its operating mechanism.

Fig. 10 is a plan view of the suction valve employed by the suction feed mechanism.

Fig. 11 is a sectional view taken on line 11-11 Fig. 10.

45 In the drawings like letters of reference indicate corresponding parts in the different views.

With reference to Figs. 1, 3, 5 and 8: The cap forms 1 are held in an open magazine which is comprised of two vertically disposed guide bars 2 and a swingable gate bar 3 which is provided with spiral springs 4 and is mounted on a vertical pivot bar 5 by hinges 6 having stop surfaces 6^x pressed by the springs 4 against the right hand bar 2. As seen in Figs. 1 and 2, the pivot bar 5 50 has an upward extension 5' to which is secured

an arcuate shaped guide plate 5^x which is held in a loosely limited position to guide the top of the pile and also serves as a buffer for the air currents from the blow tubes 74 and 75 to improve the aerating of the top cap forms of the pile. 5

The vertical guide bars 2 are secured to horizontal supporting bars 21 by L-shaped brackets 22 and the supporting bars 21 are in turn secured to a bar plate 23 which is secured to the bed plate 24 of the machine proper by a bracket 25 10 (see Fig. 2).

The vertical pivot bar 5 is rigidly secured at 2^x to one of the vertical guide bars 2. Thus the cap forms contained within the confines of the 15 vertical guide bars 2 are loosely held in a vertical stack against a rear bar 7 by the bar 3 resiliently held in place by the springs 4.

A feeding worm 8 is mounted in suitable bearings 9 and 10 and is provided with a bevel gear 11 keyed thereto which meshes with another bevel gear 12 keyed to a shaft 13 mounted in a bearing 118. On the feeding worm 8 is removably mounted a cap form supporting device which comprises two worm engaging portions 14 and 15 which are hinged one to another at 16 and are 25 provided with finger grip extension portions 17 and 18. The worm engaging portions 14 and 15 normally envelop and engage the feeding worm 8 and are held into engagement therewith by a spiral spring 19. A plate 20 is riveted or otherwise secured to the member 14 and supports the cap forms in the magazine. By squeezing the finger grip extensions 17 and 18, the worm engaging portions 14 and 15 may be spread and readily disengaged from the feeding worm 8 to 30 disengage the cap form supporter from the upper portion of the feed worm and permit its re-engagement at a lower point beneath a new stack of cap forms to serve as a support therefor after the magazine is refilled. 40

A stack or pile of cap forms are thus held in the magazine and the top cap form normally assumes the position indicated by the uppermost dot dash line A in Fig. 2 for engagement by the pneumatic feed pad 21' hereinafter described. 45 Should the level of the top cap form tend to fall below the lowermost dot dash line B in Fig. 2 so as to be beyond the influence of the suction pad 21', means are provided which will automatically elevate the cap forms until they reach 50 the level indicated by the uppermost dot dash line. This mechanism I will describe later.

I will now describe the means for picking off and transferring the cap forms.

55 26 is a suction pipe which has at one end a

downwardly extending portion 27 which is provided with a perforated suction pad 27' and is secured in a coupling 28 at its opposite end. The coupling 28 connects the suction pipe 26 to a flexible hose 29 which is in turn connected to a suction valve and thence to any suitable suction pump, such pump not being shown.

The coupling 28 is an integral part of the bracket 30 and is loose on the shaft 31 (see Figs. 10, 3 and 9). A lever 32 is also loose on the shaft 31 and integral with the bracket 28 and is connected to a link 33 which is in turn connected to the bell crank cam arm 34 which is provided with a cam roller 35. The cam roller 35 is pressed against the surface of a plate cam 36 by a spring 35^x. The cam plate is mounted upon a power shaft 37. The arm 34 is loosely mounted upon a shaft 38 mounted in the bracket 25. The shaft 38 is yoked to the shaft 31 by the tie link 39 which is fixed to the shafts 38 and 31. At the opposite end of shaft 38 is fixed a cam arm 40 which is provided with a roller 41, such roller resting against the surface of the cam 42. A spring 43 (see Fig. 9) is attached at one end to the tie link 39 and at its opposite end to a pin which is secured to an extension bracket 44 of the plate 23 and serves to keep the cam roller 41 in contact with the periphery of the cam 42. Intermediately of the cam arm 40 and the tie link 39 is a bearing bracket 41 which is secured to the bed plate 24 of the machine proper and serves with the bracket 25 to support the shaft 38.

It will thus be seen from Figs. 3 and 9 that by 35 the rotation of the power shaft 37, the cam 42 will cause the suction pipe 26 to be reciprocated vertically by the shaft 38 and tie link 39 and is, at the same time, held in a vertical position by the arm 32. The cam 36 then operates reciprocating the suction pipe in a horizontal direction through the medium of the cam 36, the bell crank cam arm 34, link 33 and lever 32.

45 is a suction valve housing which is secured to the bed plate 24 of the machine proper and which houses a valve core 46 and is provided with an intake port 47 and an outlet port 48 (see Figs. 10 and 11). The valve core 46 is provided with a communication port 49 and two extensions of reduced diameter 50 and 51 which 50 extend outwardly through opposite ends of the valve housing 45. On the extension 50 is fixed a latching member 62 which is adapted to be engaged by a pawl 52, said pawl 52 being fixed to a rock shaft 53. The rock shaft 53 is supported by a forked bracket 54 which is secured to the valve housing 45 as illustrated in Figs. 10 and 11 and manually operated by a hand lever 53^x (see Fig. 2). The opposite ends of the rock shaft 53 are supported by any suitable brackets. 60 To the extension 51 is fixed a lever 55 which is pivoted at its outer end to a block 56 which is slidably mounted on a connecting rod 57 and is restrained from any downward movement with relation to the connecting rod 57 by a fixed collar 65 58. Another fixed collar 59 is secured near the end of the connecting rod 57 and a compression spring 60 is disposed between the slidable block 56 and the fixed collar 59, thus consummating a 70 yieldable connection between the valve operating lever 55 and the connecting rod 57. The lower end of the connecting rod 57 is pivoted to a bell crank cam arm 63 which is fulcrumed on the shaft 64 and carries a cam roller 65 at its opposite 75 end. The cam roller is held against the periphery

of a cam 66 by the spring 60 and is fixed to a drive shaft 67, as clearly shown in Fig. 9.

The purpose of this particular mechanism is to provide means for shutting off the suction, to stop the feeding of the cap forms when the machine is not in operation. When it is necessary to feed cap forms in the machine, the pawl 52 is rocked to the dotted line position shown in Fig. 9 to disengage it from the latching member 62. With the pawl 52 in this position, rotation of the cam 66 will cause the valve core 46 to be oscillated bringing the communication port 49 in alignment with the ports 47 and 48 (see Figs. 9 and 11). Hence, suction is applied to the suction pad 27' and will draw a cap form up against said suction pad. The suction pipe 26 is then elevated and reciprocated forwardly by the afore-described mechanism relating to the cams 36 and 42 carrying the cap form with it and placing said cap form edgewise into the bite of the two rollers 68 and 69 (see Fig. 2) by which it is carried into the conveyor 69^x to a position for printing.

When it is desirable not to feed cap forms, the pawl 52 is moved to the full line or latching position as shown in Fig. 9. With the pawl 52 in its latching position any valve action is blocked and the rotation of the cam 66 will cause the spring 60 to yield. In this manner no suction is imparted to the suction pad 27' and consequently no cap forms will be fed into the machine.

Means are provided to assure the feeding of one cap form at a time and such means will now be described.

In proximity to the tops of the guide bars 2 are provided two leaf springs 70 and 71 which are bent (as shown in Fig. 1) across the path taken by the cap form when it is sucked against the suction pad 27'. Two blowers 74 and 75 are provided in a position illustrated in Figs. 3 and 5 and at a point just below the leaf springs 70 and 71, (see Figs. 1, 3, 5 and 8). The blowers 74 and 75 serve as agitators which separate the cap forms. When a cap form is suction raised against the suction pad 27' all of the cap forms in the proximity of the blowers 74 and 75 are in a state of agitation and the top cap form will be snapped over the leaf springs 70 and 71 and will be arrested against the suction pad 27'. The cap form which is being raised will substantially reduce the suction effecting the cap forms remaining in the magazine and the leaf springs 70 and 71 are of sufficient strength to prohibit the feeding of any other cap form which, under the influence of 55 escaping suction, may have the tendency to follow the cap form being fed.

The mechanism for automatically elevating the cap forms in the magazine when they fall below a predetermined level will now be described.

When the cap forms are primarily placed in the magazine, the cap form retaining device is placed in such a position on the feeding worm 8 as to locate the top form in a position approximating the uppermost dot dash line A shown in Fig. 2. When the machine is started the forms will be fed into the machine through the medium of the mechanism heretofore described. A sensing finger 76 (see Figs. 1 and 4) will follow the level of the cap forms under spring tension as 70 the level of the cap forms lowers. The sensing finger 76 is fixed to a block 77 which is in turn fixed to a shaft 78. The shaft 78 is journaled to a lug extension 79 of the bearing 9 and at its opposite end is fixed a lever 80. The lever 80 is 75

provided with a set screw 81 which coacts against the tail end 84^x of a latch 84. The latch 84 is pivoted to a pin 85 which is mounted on a bracket extension 86 of the bearing 9. The bracket extension 86 is in turn supported by the plate 23 (see Figs. 2, 3, 4 and 5). At the opposite end of the latch 84 is a toothed portion 84^x which is adapted to engage a recessed portion 87^x in an operating bar 87. The operating bar 87 is slidably mounted in two brackets 88 and 89. The brackets 88 and 89 are secured to the plate 23 as clearly seen in Fig. 4. 90 is a substantially L-shaped bracket which is secured to the lowermost portion of the operating bar 87 and is provided, at its outer end, with a vertical groove 115. A dog 91 is pivotally mounted on the outer extension of the bracket 90. A leaf spring 92 serves to keep the dog 91 in engagement with the ratchet 95 which is keyed to the shaft 13. A guide plate 116 slidable in the groove 115 is fixed at its opposite end to a boss 117 integral with the bearing 118 in which the shaft 113 is mounted.

A groove cam 96 (see Fig. 2) is provided with a cam roller 97 which is mounted on one end of a bell crank 98. The bell crank 98 is fulcrumed on a shaft 99 and is connected at its opposite end to a connecting rod 100. A roller 101 is mounted on the operating bar 87 and is adapted to rest against a block 102 on the bell crank 98 under the influence of a spring 103 as clearly seen in Fig. 4. The connecting rod 100 is slidably mounted at its uppermost extremity in a block 105 and is provided with a fixed collar 106 and a compression spring 109, a similar arrangement to that described in connection with the suction valve mechanism except provision has been made for spring tension adjustment by the application of the adjusting nuts 107. Pivotably mounted to the block 105 is an arm 108 which has the shaft 78 40 as its fixed pivot.

With the cap forms in their normal feeding position, that is to say, with the level of the top form intermediate of the two dot dash lines shown in Fig. 2, the sensing finger 86 will hold the lever 80 with a slight clearance to the latch 84 and thus the latch 84 will be held in engagement with the recessed portion of the operating bar 87. Consequently, when the groove cam 96 rotates the operating bar 87 will be unable to follow the movement of the bell crank 98 under the influence of the spring 103 and the spring 109 will yield in a manner similar to that of the suction valve mechanism.

However, should the level of the uppermost cap form drop below the lowermost dot dash line, shown in Fig. 2, the sensing finger will drop and raise the lever 80 which will disengage the latch 84 from the recessed portion of the operating bar 87. This function releases the operating bar 87 and will permit it to move downwardly under the influence of the spring 103 when the bell crank 98 is actuated by the cam 96. The L-shaped bracket 90 will also move downwardly with the operating bar carrying the dog 91 over the teeth of the ratchet 95. As the cam 96 returns to its normal position the bell crank 98 will power drive the operating bar 87 upwardly to actuate the ratchet and turn the worm shaft 8 through the bevel gears 12 and 11. The worm shaft 8 will thus be rotated through the cap form supporting device and inasmuch as the cap form retaining device is held against rotation it will be elevated until the cap form level raises the sensing finger to cause the latch 84 to engage the operating bar 87.

I will now briefly describe the operation of the device.

By the operation of the cam 42, arm 40 and the shaft 38, the tie link 39 is rocked downwardly in the direction of arrow (see Fig. 9) carrying the suction pad 27' into close proximity to the uppermost cap form of the stack separated from the rest of the stack and held against the spring fingers 70 by the air jets 74 and 75. The valve core 46 is turned to the open position admitting suction to the pad 27' thereby lifting the uppermost cap form into contact with the pad. The cam 42 then swings the tie link 39 upwardly in the opposite direction to arrow (see Fig. 9) lifting the suction pad 27' and the cap form engaged therewith upward past the fingers 70. The cam 36 through the arm 34, link 33 and arm 32 swings the suction pipe 26 forward carrying the cap form into the bite of the rollers 68 and 69. The valve core 46 is then turned to the closed position cutting off the suction from the pad 27' and releasing the cap form so that it is drawn into the rollers 68 and 69 as they rotate. The suction pipe 26 is then swung back to its normal position.

As the cap forms are taken from the top of the stack, the stack, of course, decreases in height so that the top cap of the stack would sink out of the range of the suction pad. To overcome this, the stack is automatically raised by means operated by the sensing finger 76 as it follows the top level of the stack downward.

The downward swing of the sensing finger 76 carries the lever 80 against the tail end 84^x of the latch 84 swinging the latch out of engagement with the recesses 87^x of the operating bar 87 which is then forced downward by the spring 103 carrying the roller 101 against the block 102 of the bell crank 98 which is continuously reciprocated by the cam 96. As the bell crank 98 swings down, the bar 87 is lowered, the roller 101 following down and thereby carrying the dog 91 idly over the teeth ratchet 35. On the upward swing of the bell crank 98, the roller 101 and bar 87 are lifted carrying the dog into engagement with the teeth of the ratchet 95 to rotate the ratchet shaft 13 and feed screw 8 through bevel gears 11 and 12 to carry the stack upwardly and the uppermost cap form to the feeding position A. The sensing finger 76 being then engaged by the top of the stack is swung upwardly carrying the lever 80 away from the tail end 84^x of the latch 84 which then engages the bar 87 to engage the recess 87^x thereby stopping the operation of the bar 87 and the rotation of the feed screw 8 through the dog 91 and ratchet 95 and the connecting gears 11 and 12.

Two cap supporting plates 20 and the means for detachably connecting them to the feed screw 8 may be employed so that as the feeding of one pile is nearly complete and the plate supporting it is near the top of the feed screw 8 another plate carrying a new pile may be inserted beneath the old pile and the support of the old pile removed as the last cap form is fed leaving the top of the new pile in the feeding position thereby rendering the feed continuous.

What I claim as my invention is:—

1. A cap form feeding device comprising a magazine for holding a vertical stack of cap forms, a perforated suction pad, a pivotally mounted suction tube leading thereto, means for lowering the pivotal mounting of the tube in a vertical plane to carry the tube downward and the pad into proximity to the uppermost cap

form to draw the same into contact therewith and for then raising the tube and its mounting, means for swinging the pad bearing end of the tube forward to convey the cap form adhering thereto to a point of deposit, and means for temporarily cutting off the suction from the tube to release the cap form.

2. A cap form feeding device comprising a magazine for holding a vertical stack of cap forms having the top maintained at a constant level, a pivoted suction lifting means, means for reciprocating the suction lifting means towards the top of the stack to grip the uppermost cap form and away from the stack top to lift the gripped form, and means for gripping the cap form carried forward to draw it edgewise from the suction pad at the point of deposit.

3. A cap form feeding device comprising a magazine for holding a vertical stack of cap forms, a rock shaft, a tie link secured thereto, a parallel shaft journalled in the opposite end of the tie link, a bracket secured to one end of the parallel shaft, a suction pipe carried in a vertical position in the bracket, a perforated suction pad 25 to which the suction pipe leads, an arm secured to the opposite end of the parallel shaft, means for rocking the shaft to swing the tie link, suction pipe and suction pad downwardly into position to lift the cap form, and means for rocking the supplemental rock shaft, suction pipe and pad forwardly to carry the lifted form to the point of deposit.

4. A cap form feeding device comprising a magazine for holding a vertical stack of cap forms, a perforated suction pad, a pipe for supplying suction to the pad, means for lowering the pad into proximity with the face of the uppermost cap form of the stack to pick up the form by its suction and for then raising the pad, means for carrying the raised pad forward with the lifted cap form, a valve in the suction pipe, a suitably driven shaft, a cam thereon, a cylindrical valve, a valve casing interposed in the length of the suction pipe, an arm secured to one end of the valve, a cam arm mounted to rock, a roller on the arm engaging the cam, a rod pivoted to the arm, a block pivoted to the valve arm over which the aforesaid rod freely extends, a stop on the rod beneath the block, a stop on the rod above the block, and a compression spring between the upper stop and the block.

5. A cap form feeding device comprising a magazine for holding a vertical stack of cap forms, a perforated suction pad, a pipe for supplying suction to the pad, means for lowering

the pad into proximity with the face of the uppermost cap form of the stack to pick up the form by its suction and for then raising the pad, means for carrying the raised pad forward with the lifted cap form, a valve in the suction pipe, a suitably driven shaft, a cam thereon, a cylindrical valve, a valve casing interposed in the length of the suction pipe, an arm secured to one end of the valve, a cam arm, a rod connecting the cam arm to the valve arm, a latching member 10 extending from the opposite end of the valve, a rock shaft journalled in bearings, a handle secured thereto, a latching pawl secured to the rock shaft and adapted to be overthrown into and out of engagement with the latching member to lock 15 the valve in a closed position, and means permitting the continued operation of the cam arms and rod when the valve is locked stationary.

6. A cap form feeding device comprising a magazine for holding a vertical stack of cap forms having the top of the stack maintained at approximately constant level, a link pivotally mounted at one end, a vertical suction tube pivotally mounted at its lower end on the free end of the link, means for reciprocating the link vertically, means for maintaining the vertical position of the suction tube during the swinging movement of the link and for reciprocating the upper end of the tube horizontally to carry the lifted cap form to the point for deposit.

7. The combination with a pivoted suction pipe having a suction orifice at its end, of means for lowering the suction end adjacent to the top of a stack of cap forms to lift a cap form, means for then swinging the pipe forward on its pivot to 35 carry the lifted form to the point of deposit, a main suction pipe, a controlling valve therein, manually operated means for locking the valve in the closed position, cam mechanism for operating the valve, and a resiliently yieldable portion 40 in such cam mechanism for permitting its continued operation when the valve is manually locked closed.

8. A cap form feeding device comprising a magazine for holding a vertical stack of cap forms, having the top maintained at approximately constant level, a vertical suction tube parallel to the height of the stack and pivotally mounted at its lower end and having its upper end formed to overhang and oppose the top of the 50 stack, means for reciprocating the suction tube longitudinally to lift the cap form, and means for swinging the suction tube forward at its upper end together with the lifted form.

IRVING F. MANDELL. 55
